UNITED STATES PATENT OFFICE.

WILHELM KRÄMER, OF GELSENKIRCHEN, GERMANY.

BRAKE FOR RAILWAY-CARS.

No. 830,156.

Specification of Letters Patent.

Patented Sept. 4, 1906.

Application filed February 28, 1906. Serial No. 303,384.

To all whom it may concern:

Be it known that I, WILHELM KRÄMER, a subject of the German Emperor, and a resident of Gelsenkirchen, Germany, have invented new and useful Improvements in Brakes for Railway-Cars, of which the following is a specification.

This invention relates to improvements in railway-brakes; and its object is to stop the train from running as quickly as possible.

The invention consists in that to the hitherto employed brake a supplementary brake is added, the brake-blocks being connected with a lever system which is actuated by a compressed-air cylinder, whereby the brake-blocks are moved downward, so that they come, besides being pressed against the circumference of the wheels, in contact with the rails. By these means a greatest possible friction is obtained by which the train is stopped practically instantly.

The construction which is shown in the accompanying drawing is as follows: The additional brake is provided below the framework of the railway-car. *a* is the compressed-air cylinder, the piston-rod of which is pivotally connected with a lever *b*, which, like the lever *c* and the double-armed lever *d*, is rigidly fixed on a common axle. A rod *e* which is pivotally connected with the lower arm of the lever *d* is in turn pivotally connected with levers *f* and *g*, which are centered in the framework of the car at *h* and in a projection *i* of the brake-block, respectively. To the upper arm of the double-armed lever *d* a rod *e'* is attached, which in a similar manner as rod *e* is in connection with levers *f'* and *g'*, centered at *h'* in the framework of the car and in a projection *i'* of the brake-block, respectively. A rod *k*, which is attached to lever *c* is in connection with the identical brake-lever system for the other wheel of the car by being attached to the double-armed lever *d* of this system.

The operation of this additional brake is as follows: If the train is to be stopped, the valve actuating the compressed-air cylinder

a is opened, whereby the piston of the latter is pushed out, thereby turning lever *b*, and consequently the double-armed lever *d*, 50 which attracts by its rods *e* and *e'*, respectively, the levers *f* and *g* and *f'* and *g'*, whereby the brake-blocks are moved downward, so that they come in contact with the rails and produce a very great friction, owing to 55 which the train is quickly brought to stopping. The brake-blocks of the other wheel are actuated in identical manner by the rod *k*, connecting the lever system for the same with that for the first wheel. 60

Having fully described my invention, what I claim, and desire to secure by Letters Patent, is—

An additional brake for railway-cars, comprising in combination with a compressed-air cylinder *a*, a lever *b* pivotally connected to the piston-rod of said cylinder and rigidly fixed on an axle, a lever *c* also rigidly fixed to said axle, a double-armed lever *d* also rigidly fixed to said axle, a rod *e* pivotally connected 65 to the lower arm of said lever *d*, two levers *f* and *g* pivotally connected to said rod *e* and centered at *h* in the framework of the car and in a projection *i* of one brake-block respectively, a rod *e'* pivotally connected to the upper 70 arm of said lever *d*, two levers *f'* and *g'* pivotally connected to said rod *e'* and centered at *h'* in the framework of the car and in a projection *i'* of the other brake-block respectively; a rod *k* attached with one end to said lever *c* and 75 with the other end to the double-armed lever *d* of the identical lever system for the second wheel, substantially as described and shown and for the purpose of moving the brake-blocks downward and bringing them in frictional contact with the rails upon the compressed-air cylinder being actuated. 80 85

In testimony whereof I have hereunto set my hand in the presence of two subscribing witnesses.

WILHELM KRÄMER.
